UNITED STATES PATENT OFFICE.

THOMAS CHARLTON, OF CHICAGO, ILLINOIS.

CONCENTRATOR.

Application filed January 17, 1921. Serial No. 427,973.

To all whom it may concern:

Be it known that I, THOMAS CHARLTON, a citizen of the United States, residing at Chicago, in the county of Cook and State of Illinois, have invented certain new and useful Improvements in Concentrators, of which the following is a specification.

This invention relates to improvements in concentrators particularly adapted, though not necessarily limited in its use for wet separation of mineral elements from each other and from the rock, and is also adapted as a deslimmer, and one of the objects of the invention is to provide an improved apparatus of this character by means of which a clean and thorough separation of the elements and parts of the material will be affected.

To the attainment of these ends, and the accomplishment of other new and useful objects as will appear, the invention consists in the features of novelty in substantially the construction, combination and arrangement of the several parts hereinafter more fully described and claimed and shown in the accompanying drawings illustrating this invention, and in which—

Figure 1 is a side elevation showing two separating elements or units connected together.

Figure 2 is a detail top plan view of the cover of one of the elements.

Figure 3 is a detail view of one of the delivery chutes.

Figure 4 is a view partly in side elevation and partly in section of one of the separator elements or units.

Figure 5 is a sectional view on line 5—5, of Figure 4.

Figure 6 is a top plan view of Figure 4.

Figure 7 is a horizontal sectional view on line 7—7, Figure 4.

Figure 8 is a view of a detail.

Figure 9 is an enlarged view in section, of a detail.

Referring more particularly to the drawings, the numeral 10 designates a supporting structure of any desired size and configuration and upon which the mechanism is mounted, carried by the supporting structure are uprights 11, 12, which are spaced from each other to receive therebetween one end of a connecting rod 13. Journaled in the uprights 11, 12, to extend across the space therebetween and at a suitable dis-

tance above the support 10, is a shaft 14, and connected with the shaft, preferably intermediate the uprights, is an eccentric 15, and to which eccentric one end of the connecting rod 13, is connected by means of the usual eccentric strap or bearing 16.

The other end of the connecting rod 13, projects for a suitable distance beyond the uprights and is bifurcated at its forward end as at 17, to form spaced arms 18—19, and between which arms a cross head 20, is pivotally supported by means of trunnions 21, so that the cross head will be movable with the connecting rod, and also with respect thereto. The cross head 20, is provided with a threaded opening 22, therethrough to receive a threaded boss or projection 23, which is connected with and depends below the bottom of a separator pan or receptacle 24, so that the latter will be supported by the connecting rod 13.

This pan or receptacle may be of any desired size and configuration, but is preferably rectangular in cross section with the bottom 25, inclining from the sides and ends of the receptacle towards the center thereof so as to direct the separated element which gravitates to the bottom of the receptacle, towards a discharge outlet opening 26, the wall of which outlet adjacent the bottom of the receptacle is shaped to form a valve seat. The receptacle is provided with a discharge or overflow spout 27, along one side thereof leading from the top of the receptacle, and a cover 28, is provided for the receptacle. This cover is removably secured in position in any suitable manner, such as by means of fastening bolts 29, and a portion of the cover is shaped to form a flange 30, which extends over and forms a part of the discharge spout 27.

Carried by the cover 28, and depending therefrom into the receptacle, but terminating a considerable distance above the bottom of the receptacle and in alignment with the discharge outlet 26, is a stem or guide 31, which is removably secured to the cover in any suitable manner such as by means of the threaded extremity 32, thereof.

A tubular valve element 33, telescopes with the guide 31, and is adapted to be moved freely thereupon, one end of this element 33, being shaped to form a valve proper adapted to cooperate with the valve seat around the opening 26, to close the

opening when the valve is seated and thereby retain the precipitated element within the receptacle until the valve element 33, is shifted to open the outlet 26.

- 5 When the valve element 33, is thus unseated the material will flow through the outlet from the receptacle 24, and will be discharged through an opening 34, in the projection 23, carried by the receptacle 24, 10 and will then be received by a chute or delivery conduit 35, having an enlarged or funnel shaped extremity 36, adjacent the outlet or opening 34, and which chute 35, is supported preferably by the support 10.
- 15 The discharge outlet 26, is automatically opened and closed by the valve element 33, by a rising and falling movement of the receptacle 24, and which movement is automatically controlled by the weight of the 20 material accumulated in the receptacle.

To that end the receptacle 24, is held in its elevated position by means of a scale beam 37, mounted intermediate its ends upon the suitable knife edge bearing 38, and 25 which beam is connected with the receptacle 24, by means of suitable links 39, two of which are preferably provided. Each link is preferably provided with heads 40—41, the head 40, engaging in a suitable open 30 bearing 42, on the scale beam and the head 41, engages a similar bearing 43, preferably carried by the connecting rod 13, and depending therefrom. Each of these bearings is provided with an opening 44, so that the 35 head 40, may be seated in the bearing from the side thereof, the walls of the bearing being preferably inclined as at 45, so as not to interfere with the relative movement of the link with respect to the bearing during 40 the operation of the mechanism, as will be understood.

Connected also with the scale beam is an adjustable weight 46, adjusted in any suitable manner such as by means of the adjusting 45 bolt or element 47.

An adjustable stop device 48, is provided for limiting the movement of the beam in one direction, and this stop device is preferably carried by the beam and adapted to 50 engage the support 10.

Any suitable means may be provided for maintaining the valve element 33, against movement during the raising and lowering movements of the receptacle 24, so as to 55 cause the discharge outlet 26, to be opened and closed by such movements of the receptacle. To that end a link 49, is pivotally anchored by one end 50, preferably to the delivery chute 35, by extending into the 60 entrance opening 36, thereof so that a pin 51, which passes through the wall of such entrance opening will also pass through the end 50 of the link.

The other end 52, of the link passes 65 through the opening 26, in the bottom of

the receptacle 24, and into the valve element 33, terminating short of the end of the guide or projection 31, and a fastening pin 53, extends through the wall of the valve element 33 and also through the end of the 79 link 49.

Thus it will be seen that inasmuch as the valve element 33, is held stationary with respect to the support 10, and as the chamber 24, is adapted for a pivotal movement about 75 the eccentric 15, in one direction under the influence of the scale beam 37, and in the opposite direction under the influence of the accumulating material in the receptacle 24, the outlet 26, will be automatically closed 80 and opened. By adjusting the weight 46, upon the scale beam 37, it will be manifest that the weight which is necessary to move the receptacle 24, by the accumulating material therein, may be varied at will. A 85 vibratory movement is imparted to the receptacle 24, through the medium of the eccentric 15, and the connecting rod 13, and the vibratory movement and rising and falling movements of the receptacle 24, will not 90 interfere with the operation of either of them.

A vibratory movement is imparted to the receptacle for the purpose of agitating the material in the receptacle and for causing 95 the elements to automatically separate with the result that the heaviest element will gravitate through the other elements to be precipitated to the bottom of the receptacle and there accumulate until the outlet 26, 100 is automatically opened to discharge such accumulation.

In practice it has been found that the vertical or rising and falling movements of the receptacle 24, will be very slight, due 105 to the fact that after starting the apparatus, there will be an almost constant flow of material from the outlet 26.

Motion is imparted to the eccentric 15, in any suitable manner preferably from a 110 motor 54, and suitable intermediate gear connections 55—56—57 and 58, the gear 58 being connected with the shaft 14, upon which the eccentric 15, is mounted.

The cover or top 28, is preferably provided with a chamber 59, in communication with the interior of the receptacle 24, and arranged within this chamber is a cup shaped element or structure 60, which is 115 preferably separate therefrom and held in position by means of one or more suitable fastening devices 61, so as to permit the cup to be removed when desired. This cup element is of a size somewhat less than the chamber so as to form an opening 62, to 120 permit the material discharged from or overflowing the cup, to enter the receptacle 24. This cup shaped element is employed 125 for the purpose of intercepting the material as it is fed from a supply pipe or conduit 130

63, and breaks the fall of the material into the receptacle, so that the material within the receptacle will not be unduly agitated thereby.

5 A flexible ball and socket joint 64—65, is provided between the pipe 63 and the cover 28, of the receptacle 24, so that the receptacle may be adapted for free movement with respect to the pipe 63.

10 It is sometimes desirable, according to the materials being handled, to impart to the receptacle 24, an oscillatory movement about the pivots formed by the trunnions 21, on the cross head 20, in addition to the vibratory movement imparted thereto by the eccentric 15, and connecting rod 13. This may be accomplished in the following manner:

15 Journalized upon the upright 11, is a shaft 66, which has connected therewith a disc 67, provided with a groove or slot 68, preferably dovetailed, opening through one face thereof. An element 69, is slideable freely in the groove by means of its head and the free extremity of the element is threaded as at 70. A sleeve 71 encompasses the element 70, so that the head 72, abuts the face of the disc 67, and the parts are frictionally gripped or secured with respect to each other by means of a nut 73, threaded upon the end 70, of the element 69, and an interposed washer 74, between the nut 73 and the adjacent end of the sleeve 71.

20 This element 69 is connected with the cover 28, of the receptacle 24, through the medium of a sectional connecting rod, one of the sections 75, is provided at one end with a bearing which receives the sleeve 71, and the other end thereof is threaded as at 76. The other section 77, is bifurcated as at 78, to receive a lug or projection 79, on the cover 28, and a pin 80 pivotally connects the bifurcated end of the element 78 with the lug 79.

25 The other end of the element or section 78, is threaded as at 81, in a direction opposite to the threads 76, on the section 75, and these adjacent threaded extremities are adapted to receive a turn buckle 82, so that by adjusting the turn buckle 82 the length of the connection rod embodying the two sections 75, 77, may be lengthened or shortened so as to vary the extent of oscillatory movement of the receptacle.

30 When the turn buckle 82, is adjusted it will cause the position of the element 69 in the groove 68, to be varied with respect to the axis of rotation of the disc 67, to vary the extent of such oscillatory movement, but when it is desired to maintain the receptacle 24, against such an oscillatory movement the turn buckle 82, is operated so as to cause the element 69 to be maintained at the center of the axis of rotation of the element 67, and at that time the only motion given to the receptacle 24, will be the vibra-

tory motion imparting thereto by the eccentric 15.

The oscillatory motion is imparted to the receptacle 24, for the purpose of discharging everything from the receptacle through 70 the spout 30, except the separated element that is to be taken out through the opening 26. Obviously the degree of oscillation may be varied by first adjusting the element 69 with respect to the axis of the disc 67, and 75 the angle of inclination of the receptacle may be then further adjusted by adjusting the turn buckle 82.

When the element 69 is secured at the axis of rotation of the disc 67, and it is desired 80 to incline the receptacle 24, and maintain it in an inclined position, without imparting an oscillatory motion to the receptacle, this may be accomplished by simply adjusting 85 the turn buckle 82, until the desired angularity is secured.

The shaft 66 and disc 67, may be rotated preferably from the shaft 14, through the medium of a sprocket chain 83, passing over suitable sprockets carried by the shafts 90 14 and 66. It is thought that the operation of this machine will be clearly understood from the foregoing description, but briefly stated it is as follows:

90 The element 69, is first adjusted with respect to the disc 67 to impart the desired degree of oscillation to the receptacle 24, and the motor is then started which will through the medium of the eccentric 15, and connecting rod 13, impart a vibratory movement to the receptacle at the same time that the oscillatory movement is imparted thereto by the rotation of the disc 67. The material to be separated is fed through the pipe 63, and falls into the cup 60, to be delivered 105 therefrom into the chamber 24. The motions imparted to the receptacle 24 and against the inclined bottom 25 thereof in such a manner that the unseparated material will flow or slide across the said bottom and the 110 top of the accumulated separated element in such a manner that a minimum agitation will be imparted to the accumulated separated element, will agitate the materials to the necessary extent so as to cause the heaviest material to precipitate to the bottom of the receptacle and there accumulate around the valve element 33.

115 The other elements will be discharged through the spout 30. When there has been 120 a sufficient accumulation of the separated element in the bottom of the receptacle to overcome the weight on the scale beam, the receptacle will be lowered, and as the valve element 33 is held stationary, the outlet 26 125 will be opened to permit the discharge therethrough of the accumulated separated element. When this element has been thus discharged through the opening 26, the scale beam will cause the receptacle 24 to return 130

to a position to close the outlet 26, and these operations will be continually repeated during the operation of the machine.

If desired a plurality of these separator elements may be coupled together, and in that event the material after separation has been effected thereupon in one unit, will be delivered through the spout 30, into another unit, through the medium of an intermediate spout 84, if desired, for further separation, thus utilizing each unit to remove the heaviest element contained in the material delivered thereto.

The construction and operation of each element is the same with the exception of the specific manner of delivering the material into the respective receptacles, and in each unit except the first one, the cover 85, is provided with an opening 86, to receive the end 87 of the chute 84, and the chutes 84, are bifurcated as at 88, adjacent the end 87, so as to stand astride of the connecting rods between the respective covers 85 and discs 67.

When two of these units are coupled together, a single drive chain 89, may be employed to impart motion from one of the shafts 14, to the discs 67, and if desired an idle pulley 90, may be employed for the drive chain.

Similarly a single drive chain 91, may be employed to impart motion from one of the shafts 14, to the other shaft 14.

This machine may be used as a desliming machine by permitting all the mineral elements and part of the rock to pass through the lower opening, and throwing off through the spout 30, all of the slime material and considerable of the free rock. This will curtail to a considerable degree the necessary separating capacity.

While the preferred form of the invention has been herein shown and described, it is to be understood that various changes may be made in the details of construction and in the combination and arrangement of the several parts within the scope of the claims, without departing from the spirit of this invention.

What is claimed as new is:—

1. A concentrator of the character described embodying a separator receptacle, means for supplying the material thereto, means for imparting a vibratory motion to the receptacle about a substantially horizontal pivot, means also for imparting an oscillatory movement to the receptacle, there being an overflow outlet for the material, there being also a discharge outlet through the bottom of the receptacle at substantially the center thereof for the separated element, the bottom of the receptacle inclining downwardly towards the said opening, and means for automatically controlling the last recited outlet, the last recited means co-oper-

ating with the said bottom for maintaining in the bottom of the receptacle a predetermined depth of the separated element.

2. A concentrator of the character described embodying a separator receptacle, means for supplying the material thereto, means for imparting a vibratory motion to the receptacle, means also for imparting an oscillatory movement to the receptacle, there being a substantially centrally disposed discharge outlet from the bottom of the receptacle for the separated element, the bottom of the receptacle inclining downwardly towards said outlet, and means whereby the weight of the separated element will automatically control the said outlet, the last recited means embodying provisions whereby there will be maintained in the bottom of the receptacle a predetermined depth of the separated element.

3. A concentrator of the character described embodying a separator receptacle, means for supplying the material thereto, means for imparting a vibratory motion to the receptacle, means also for imparting an oscillatory movement to the receptacle, there being a substantially centrally disposed discharge outlet through the bottom of the receptacle for the separated element, the bottom of the receptacle inclining downwardly towards said outlet, and means whereby the weight of the separated element will automatically control the said outlet, the last recited means embodying provisions whereby there will be maintained in the bottom of the receptacle a predetermined depth of the separated element, the last recited means also embodying provisions whereby the weight of the separated element necessary to open the said outlet may be varied at will.

4. A concentrator of the character described embodying a separator receptacle, means for supplying the material thereto, means for imparting a vibratory motion to the receptacle, and means for imparting a nonrotary and lateral oscillatory movement to the receptacle and about a substantially horizontal pivot, the last recited means embodying mechanism whereby the degree of oscillatory movement of the receptacle may be varied while the degree of vibratory movement of the receptacle remains constant.

5. A concentrator of the character described embodying a separator receptacle, means for supplying the material thereto, means for imparting a vibratory motion to the receptacle, and means for imparting an oscillatory movement to the receptacle about a substantially horizontal pivot, the last recited means embodying mechanism whereby the degree of oscillatory movement of the receptacle may be varied while the degree of vibratory movement of the receptacle remains constant, the said oscillatory means being also adapted to be rendered ineffective.

while the said vibratory means remains effective.

6. A concentrator of the character described embodying a separator receptacle, means for supplying the material thereto, means for imparting a vibratory motion to the receptacle, means also for imparting an oscillatory movement to the receptacle about a substantially horizontal pivot, the last recited means embodying mechanism whereby the degree of oscillatory movement of the receptacle may be varied while the degree of vibratory movement of the receptacle remains constant, there being a discharge outlet through the bottom of the receptacle for the separated element, and means for controlling said outlet.

7. A concentrator of the character described embodying a separator receptacle, means whereby material may be supplied thereto, means for imparting a vibratory motion to the receptacle, means also for imparting an oscillatory movement to the receptacle, there being a substantially centrally disposed discharge outlet through the bottom of the receptacle for the separated element, the said bottom having a slight downward inclination towards said opening whereby the material when the receptacle is vibrated will flow freely back and forth across the separated element and the said bottom, and means whereby the weight of the accumulated separated element in the receptacle will automatically control the said outlet.

8. A concentrator of the character described embodying a separator receptacle, means whereby material may be supplied thereto, means for imparting a vibratory motion to the receptacle, means also for imparting an oscillatory movement to the receptacle about a substantially horizontal pivot, there being a substantially centrally disposed discharge outlet through the bottom of the receptacle for the separated element, the said bottom having a slight downward inclination towards said opening whereby the material when the receptacle is vibrated will flow freely back and forth across the separated element and the said bottom, and means for controlling the said outlet.

9. A concentrator of the character described embodying a separator receptacle, means for supplying the material thereto, means for imparting a vibratory motion to the receptacle, means also for imparting an oscillatory movement to the receptacle about a substantially horizontal pivot, the last recited means embodying mechanism whereby the degree of oscillatory movement of the receptacle may be varied while the degree of vibratory movement of the receptacle remains constant, there being a discharge outlet for the separated element.

10. A concentrator of the character described embodying a separator receptacle, means for supplying the material thereto, means for imparting a vibratory motion to the receptacle, means also for imparting an oscillatory movement to the receptacle about a substantially horizontal pivot, the last recited means embodying mechanism whereby the degree of oscillatory movement of the receptacle may be varied while the degree of vibratory movement of the receptacle remains constant, there being a discharge outlet through a wall of the receptacle for the separated element, and means for controlling the said outlet.

11. A concentrator embodying a scale like beam, a receptacle supported thereby, and movable with the beam, said receptacle having a discharge outlet through the bottom thereof, the said bottom having a slight downward inclination towards said opening whereby the unseparated material when the receptacle is vibrated will flow freely back and forth across the separated element and the said bottom, means for supplying the material to the receptacle, means for imparting a vibratory motion to the receptacle with respect to the scale beam, and means whereby the movement of the said receptacle with the scale beam will control the said outlet, the last recited movement of the receptacle being automatically controlled by the weight of the accumulated separated element in the receptacle.

12. A concentrator embodying a separator receptacle, means supporting the receptacle for a plurality of different movements, a discharge outlet from the receptacle for the separated element, a cut-off for said outlet, the weight of the accumulated separated element in the receptacle operating to impart one of the said movements to the receptacle to open the said outlet, and means for maintaining the said cut-off against movement.

13. A concentrator embodying a separator receptacle, having a discharge outlet for the accumulated separated element, means for imparting a vibratory movement to the receptacle, means for imparting an oscillatory movement to the receptacle, the last recited means embodying provisions whereby the extent of oscillatory movement of the receptacle may be varied at will while the degree of vibratory movement remains constant, the last recited means being also adapted to be set to overcome such oscillatory motion.

14. A concentrator embodying a separator receptacle, having a discharge outlet for the accumulated separated element, means for imparting a vibratory movement to the receptacle, means for imparting an oscillatory movement to the receptacle, the last recited means embodying provisions whereby the extent of oscillatory movement of the

receptacle may be varied at will while the degree of vibratory movement remains constant, the last recited means being adapted to be set to overcome such oscillatory motion, and being also adapted to maintain the said receptacle in a fixed angular position.

15. A concentrator embodying a separator receptacle, having a discharge outlet for the accumulated separated element, means for imparting a vibratory movement to the receptacle, means for imparting an oscillatory movement to the receptacle, the last recited means embodying provisions whereby the extent of oscillatory movement of the receptacle may be varied at will while the degree of vibratory movement remains constant, the last recited means being adapted to be set to overcome such oscillatory motion and being adapted to be adjusted to position and maintain the receptacle at any desired angle of inclination.

16. A concentrator embodying a separator receptacle, supported for movement under the weight of the accumulated separated element therein, a substantially centrally disposed discharge outlet for the said element, stationary means for closing the outlet whereby the movement of the receptacle under the influence of said element will open the outlet, and means for actuating the receptacle for agitating the materials therein to cause separation of the elements and a precipitation of the heaviest element.

17. A concentrator embodying a separator receptacle, a discharge outlet for the separated element, means for actuating the receptacle for agitating the materials therein to cause separation of the elements and a precipitation of the heaviest element, and means for imparting an oscillatory movement to the receptacle, the last recited means embodying provisions for rendering the same effective and ineffective and for also varying the degree of angularity of the receptacle when the last recited means is either effective or ineffective.

18. A concentrator embodying a separator receptacle having a substantially centrally disposed discharge outlet through the bottom thereof for the separated element accumulated therein, the bottom of the receptacle inclining downwardly towards said outlet to form with the separated element an extended surface over which the material freely flows back and forth, means for agitating the receptacle, means operating automatically to control the said outlet, the last recited means also operating to maintain in the receptacle a predetermined depth of separated material, means for supplying to the receptacle the material to be separated, and means within and movable with the receptacle for intercepting the fall of the material from the last recited means.

19. A concentrator embodying a separator

receptacle having a substantially centrally disposed discharge outlet for the separated element accumulated therein, the bottom of the receptacle having a slight downward inclination towards said outlet to form with the accumulated separated element an extended surface over which the material freely flows back and forth during the separation thereof, means for agitating the receptacle, means whereby the weight of the accumulated separated element in the receptacle will automatically open the said discharge outlet, means for supplying to the receptacle the material to be separated, and means within the receptacle for intercepting the fall of the material from the last recited means.

20. A concentrator embodying a separator receptacle having a substantially centrally disposed discharge outlet for the separated element accumulated therein, the bottom of the receptacle having a slight downward inclination towards said outlet to form with the accumulated separated element and extended surface over which the material freely flows back and forth during the separation thereof, means for agitating the receptacle, means whereby the weight of the accumulated separated element in the receptacle will automatically open the said discharge outlet, means whereby the weight necessary to open the said outlet may be varied at will, means for supplying to the receptacle the material to be separated, and means within the receptacle for intercepting the fall of the material from the last recited means.

21. A concentrator embodying a separator receptacle, means for imparting a vibratory movement thereto, said receptacle having a discharge outlet for the accumulated separated element therein, the receptacle being adapted for movement under the influence of the weight of the said accumulated element, a valve for controlling the outlet, and means anchoring said valve independently of the receptacle and with respect to which valve the receptacle is bodily movable to open and close the said outlet.

22. A concentrator embodying a separator receptacle, means for imparting a vibratory movement thereto, said receptacle having a discharge outlet for the accumulated separate element therein, the receptacle being adapted for movement under the influence of the weight of the said accumulated element, a valve for controlling the outlet, means anchoring said valve independently of the receptacle and with respect to which valve the receptacle is bodily movable to open and close the said outlet, and a guide connected to and movable with the receptacle, said guide and valve embodying telescoping elements.

23. A concentrator embodying a separa-

- 10 tor receptacle, means for imparting a vibratory movement thereto, said receptacle having a discharge outlet for the accumulated separated element therein, the receptacle being adapted for movement under the influence of the weight of the said accumulated element, a valve for controlling the outlet, and means anchoring said valve independently of the receptacle and with respect to which valve the receptacle is bodily movable to open and close the said outlet, the said anchoring means operating to permit the valve to move with the receptacle during the vibratory movement of the latter for maintaining the said outlet closed. 15
- 20 24. A concentrator embodying a separator receptacle, means for imparting a vibratory movement thereto, said receptacle having a discharge outlet for the accumulated separated element therein, the receptacle being adapted for movement under the influence of the weight of the said accumulated element, a valve for controlling the outlet, and means anchoring said valve independently of the receptacle and with respect to which valve the receptacle is bodily movable to open and close the said outlet, the first recited means embodying an eccentric, a connecting rod operated thereby and a 25 pivotal connection between the connecting rod and the said receptacle for supporting the latter. 30
- 25 25. A concentrator embodying a pivotally mounted arm, a separator receptacle pivotally supported thereby, a scale beam spaced from the arm, a link connection between the arm and beam, said scale beam tending normally to move the receptacle in one direction, the receptacle being movable in the opposite direction by the weight of the accumulated separated element therein, means co-operating with the said arm for vibrating the receptacle, there being a discharge outlet from the receptacle for the 35 said accumulated separated element, and means controlled by the movements of the receptacle under the influence of the said element and the scale beam for controlling the said outlet. 40
- 45 26. A concentrator embodying a pivotally mounted arm, a separator receptacle pivotally supported thereby, a scale beam spaced from the arm, a link connection between the arm and beam, said scale beam tending normally to move the receptacle in one direction, the receptacle being movable in the opposite direction by the weight of the accumulated separated element therein, means co-operating with the said arm for 50 vibrating the receptacle, there being a discharge outlet from the receptacle for the said accumulated separated element, and means controlled by the movements of the receptacle under the influence of the said element and the scale beam for controlling the said outlet. 55
- 60 27. A concentrator embodying a pivotally mounted arm, a separator receptacle pivotally supported thereby, a scale beam spaced from the arm, a link connection between the arm and beam, said scale beam tending normally to move the receptacle in one direction, the receptacle being movable in the opposite direction by the weight of the accumulated separated element therein, means co-operating with the said arm for 65 vibrating the receptacle, there being a discharge outlet from the receptacle for the said accumulated separated element, and means controlled by the movements of the receptacle under the influence of the said element and the scale beam for controlling the said outlet, the last recited means embodying an anchored cut-off and with relation to which cut-off the said receptacle is movable. 70
- 70 28. A concentrator embodying a pivotally mounted arm, a separator receptacle pivotally supported thereby, a scale beam spaced from the arm, a link connection between the arm and beam, said scale beam tending normally to move the receptacle in one direction, the receptacle being movable in the opposite direction by the weight of the accumulated separated element therein, means co-operating with the said arm for 75 vibrating the receptacle, there being a discharge outlet from the receptacle for the said accumulated separated element, means controlled by the movements of the receptacle under the influence of the said element and the scale beam for controlling the said outlet, the last recited means embodying a cut-off, and a link pivotally connected with the cut-off and a fixed support, the said link operating to cause the said cut-off to move with the receptacle during the vibration of the latter to maintain the discharge outlet closed, and will cause the receptacle to move with relation to said cut-off during the first two recited movements of the receptacle. 80
- 80 29. A concentrator embodying a closed separator receptacle having a discharge outlet adjacent the top thereof and a discharge outlet through the bottom thereof, means for supplying the materials to the receptacle, means for imparting a vibratory movement to the receptacle to agitate the materials to cause the heaviest element to be precipitated to the bottom of the receptacle, means for controlling the discharge of the accumulated separated element through the outlet in the bottom of the receptacle, and means for imparting a simultaneous oscillatory motion to the receptacle to discharge or spill the remaining unseparated elements out of the outlet adjacent the top of the receptacle, the last recited means embodying a rotatable disc, having a slot therein, an element adjustable in the slot, an adjustable connecting rod pivotally connected at one end with the said element and at its other end with the said receptacle whereby the position of the said element in the said slot with respect to the axis of rotation of the disc may be varied at will, and means whereby the said element may be secured against movement with respect to the disc and in the position to which it has been adjusted in the slot. 85
- 90 30 29. A concentrator embodying a separator receptacle having a discharge outlet adjacent the top and a discharge outlet through the bottom thereof, means for supplying the material to the receptacle, means for imparting a vibratory movement to the receptacle. 95

tacle to agitate the materials to cause the heaviest element to be precipitated to the bottom of the receptacle, means for controlling the discharge of said element through

5 the outlet in the bottom of the receptacle, and means for imparting a simultaneous oscillatory motion to the receptacle and about a substantially horizontal pivot to discharge or spill the remaining unseparated 10 elements through the outlet adjacent the top of the receptacle.

30. An apparatus of the character described embodying a plurality of separator receptacles, independent of and separated 15 from each other, means individual to the receptacles for imparting vibratory movements thereto, means also individual to the receptacles for imparting an oscillatory movement thereto, each of said receptacles 20 being provided with a plurality of outlets, means operating automatically for respectively controlling one of the outlets of each receptacle for discharging the accumulated separated element therein, and a chute for 25 receiving the unseparated elements from the other of said outlets of one of the receptacles and delivering the same to the next adjacent receptacle.

31. An apparatus of the character described embodying a plurality of separator receptacles, independent of and separated from each other, means individual to the receptacles for imparting vibratory movements thereto, means also individual to the 35 receptacles for imparting an oscillatory movement thereto, each of said receptacles being provided with a plurality of outlets, means controlled by the weight of the accumulated separated element in each of the 40 receptacles and operating automatically for respectively controlling one of the outlets of each receptacle for discharging the accumulated separated element therein, and a chute for receiving the unseparated elements 45 from the other of said outlets of one of the receptacles and delivering the same to the next adjacent receptacle.

32. An apparatus of the character described embodying a plurality of separator 50 receptacles independent of and separated from each other, means individual to the receptacles for imparting vibratory movements thereto, means also individual to the receptacles for imparting an oscillatory 55 movement thereto, each of said receptacles being provided with a plurality of outlets, means operating automatically for respectively controlling one of the outlets of each receptacle for discharging the accumulated 60 separated element therein, and a chute for receiving the unseparated elements from the other of said outlets of one of the receptacles and delivering the same to the next adjacent receptacle, the respective second 65 recited means embodying provisions where-

by the degree of oscillatory movement of the respective receptacles may be varied at will while the degree of their respective vibratory movements remain constant.

33. A concentrator embodying a separator 70 receptacle, means for delivering thereto the materials to be separated, means for vibrating the receptacle for agitating the material to cause the heaviest element to be precipitated to the bottom, and selective means 75 whereby an oscillatory movement may be imparted to the receptacle about a substantially horizontal pivot simultaneously with the vibratory movement, or whereby the receptacle may be maintained in a fixed position 80 during such vibratory movement thereof.

34. A concentrator embodying a separator receptacle, means for delivering thereto the materials to be separated, means for vibrating 85 the receptacle for agitating the material to cause the heaviest element to be precipitated to the bottom and selective means whereby an oscillatory movement about a substantially horizontal pivot may be imparted to the receptacle simultaneously 90 with the vibratory movement, or whereby the receptacle may be maintained in a fixed position during such vibratory movement thereof, the said selective means 95 being also adapted to vary the angularity of the receptacle independent of the said oscillatory movement.

35. A concentrator of the character described embodying a separator receptacle, 100 means for supplying the material thereto, means for imparting a vibratory motion to the receptacle, means for imparting an oscillatory movement to the receptacle, there being a discharge outlet through the bottom 105 of the receptacle for the separated element, said bottom having a slight downward inclination towards the said outlet whereby the material when the receptacle is vibrated will flow freely back and forth across the accumulated separated element and the said bottom, and means movable with the receptacle 110 and operating to intercept the fall of the unseparated material into the receptacle.

36. A concentrator of the character described embodying a separator receptacle, 115 means for supplying the material thereto, means for imparting a vibratory motion to the receptacle, means for imparting an oscillatory movement to the receptacle, there 120 being a discharge outlet through the bottom of the receptacle for the separated element, the said bottom having a slight downward inclination towards the said outlet whereby the material when the receptacle is vibrated 125 will flow freely back and forth across the accumulated separated element and the said bottom, and means movable with the receptacle and operating to intercept the fall of the unseparated material into the receptacle, 130

the last recited means also operating to distribute the incoming unseparated material across the said bottom and the top of the accumulated separated element with a minimum agitating operation upon the said separated element.

37. The method of separating mineral elements from each other and from the rock, which consists in subjecting a mass of 10 crushed or pulverized material containing the elements to a vibratory motion to agitate the mass and thereby cause the heaviest element to be precipitated to the bottom of the mass, then removing or discharging the 15 remaining unseparated elements by imparting another and different bodily movement to the mass so as not to disturb the accumulated separated element, and while the heaviest element is at the bottom of the mass, 20 and finally automatically carrying away the accumulated separate element.

38. A concentrator embodying a separator receptacle, said receptacle having a discharge outlet through the bottom thereof, 25 the said bottom having a slight downward inclination towards said opening whereby the material to be separated will, when the receptacle is vibrated, flow freely back and

forth across the accumulated separated element and the said bottom, means for supplying material to the receptacle, means for imparting a vibratory motion to the receptacle, and means whereby the movement of the said receptacle will control the said outlet, the last recited movement of the receptacle being automatically controlled by the weight of the accumulated separated element in the receptacle. 30 35

39. A concentrator embodying a separator receptacle, said receptacle having a discharge outlet through the bottom thereof, 40 the said bottom having a slight downward inclination towards said opening whereby the material to be separated will, when the receptacle is vibrated, flow freely back and 45 forth across the accumulated separated element and the said bottom, means for supplying material to the receptacle, means for imparting a vibratory motion to the receptacle, and means for automatically controlling the 50 said outlet.

In testimony whereof I have signed my name to this specification, on this 14th day of January, A. D. 1921.

THOMAS CHARLTON.
